CLAIM

The ornamental design for a display screen or portion thereof with animated graphical user interface, as shown and described herein.

DESCRIPTION

FIG. 1 is a frontal view of a first image in a sequence of a display screen or portion thereof with animated graphical user interface, according to a first embodiment.

FIG. 2 is a frontal view of a second image in a sequence of a display screen or portion thereof with animated graphical user interface, according to a first embodiment.

FIG. 3 is a frontal view of a third image in a sequence of a display screen or portion thereof with animated graphical user interface, according to a first embodiment.

FIG. 4 is a frontal view of a fourth image in a sequence of a display screen or portion thereof with animated graphical user interface, according to a first embodiment.

FIG. 5 is a frontal view of a fifth image in a sequence of a display screen or portion thereof with animated graphical user interface, according to a first embodiment.

FIG. 6 is a frontal view of a first image in a sequence of a display screen or portion thereof with animated graphical user interface, according to a second embodiment.

FIG. 7 is a frontal view of a second image in a sequence of a display screen or portion thereof with animated graphical user interface, according to a second embodiment.

FIG. 8 is a frontal view of a third image in a sequence of a display screen or portion thereof with animated graphical user interface, according to a second embodiment.

FIG. 9 is a frontal view of a fourth image in a sequence of a display screen or portion thereof with animated graphical user interface, according to a second embodiment; and,

FIG. 10 is a frontal view of a fifth image in a sequence of a display screen or portion thereof with animated graphical user interface, according to a second embodiment.

The outermost broken line rectangle shows the display screen or portion thereof and forms no part of the claimed design. All other broken lines show portions of the graphical user interface and form no part of the claimed design. The appearance of the transitional image sequentially transitions between the images shown in FIGS. 1-5 and FIGS. 6-10, respectively.

The process of period in which one image transitions to another image forms no part of the claimed design.
